DEPOSITION FORM

Graham G. Wanless, Montreal, Quebec, Canada, assignor, by mesne assignments, to United States Rubber Company, New York, N. Y., a corporation of New Jersey

Application July 8, 1937, Serial No. 152,587

1 Claim. (Cl. 18—41)

This invention relates to a deposition form upon which a rubber coating may be deposited for the production of a pouch on each end thereof.

This invention is an improvement upon a double end deposition form disclosed in an application of Harold D. Rice, Serial No. 152,585, filed July 8, 1937. The form described by Harold D. Rice is provided with a pair of spaced parallel grooves which extends around the form to produce reinforcing beads on the rim of the mouths or the mouths and flaps of the pouches deposited thereon. The strip of coating deposited on the surface of the form between the grooves is severed so that the pouches can be removed from the opposite ends of the form. After the pouches are removed it is necessary to trim the edges along the mouths and the flaps of the pouches in the event the grooves are separated a substantial amount. In the present invention an improved construction is provided for removing the strip of coating extending between the beads of the respective pouches and to obviate the necessity of the subsequent trimming of the edges along such beads after the pouches are removed from the form.

The foregoing advantages and other important features of this invention will be more clearly understood by referring to the following description and the accompanying drawing in which:

Fig. 1 is an isometric view of a deposition form embodying this invention;

Fig. 2 is a cross-sectional view of the form on line 2—2 of Fig. 1;

Fig. 3 is an isometric view of a pouch produced on such form; and

Fig. 4 is a fragmentary view of a modification of the invention shown in Figs. 1 to 3, in which grooves are shown at the base of the ridge for separating the pouches when deposited on the end of the deposition form.

This invention is illustrated in reference to a pouch P (Fig. 3) having a pocket portion P' and a mouth M and a flap F for closing same, the edges of which are provided with a reinforcing bead B. The form may be made of hard vulcanized rubber, aluminum or other suitable deposition material. It is provided with opposite side deposition surfaces 11 and opposite edge deposition surfaces 12 extending between and contiguous to the side surfaces 11, which surfaces are adapted to be completely covered with a rubber coating deposited thereon from

an aqueous dispersion of rubber to produce a pouch P on each of the opposite ends 13 of the form, the pocket P' of the respective pouches being formed on the opposite ends 13 and the mouth M and flap F being formed on the intermediate portion 14 of the form. A surface formation is formed on the intermediate portion 14 to produce the bead B on the mouth and flap of each pouch and to indicate the line of separation between the pouches. As illustrated, the surface formation comprises an abruptly rising ridge 15 extending across the side surfaces 11 at offset positions 16 and extending along the edge surfaces 12 between the two positions. The rubber deposited from the aqueous dispersions of rubber collects in the corners 17 and 18 formed between the side edges of the ridge and the deposition surfaces 11 and 12 of the form to produce the bead B on the pouch P. The bead B of the pouch P deposited on the left end of the form as viewed in Fig. 1 is formed in the corner 17. The bead B of the pouch P deposited on the right end of the form 10 as viewed in Fig. 1 is formed in the corner 18.

The corners 17 and 18 should be relatively sharp to collect a large amount of rubber for the production of thick beads, but they may be slightly rounded as by a small fillet. The thickness of the bead may be increased by undercutting the sides of the ridge 15 or by providing grooves 22 and 23 along the base of the ridge 15, as shown in Fig. 4. The top corners of the ridge should also be relatively sharp so that the surface tension of the rubber coating across the top of the ridge 15 will produce a weak line in such coating along the top corners.

The top surface of the ridge 15 is made relatively narrow, but sufficiently wide to receive the handle 19 provided with a foot 20 anchored in the form 10. The upper end of the handle 10 is provided with nuts 21 for securing the handle to a mechanism for conveying the form through a dipping or spraying bath of an aqueous dispersion of rubber.

The rubber coating may be deposited on the form in the conventional manner by either dipping or spraying the form with a suitably compounded aqueous dispersion of rubber.

After the desired thickness of rubber coating has been coagulated and dried on the form, the strip of coating on the top of the ridge is connected to the beads B on the respective pouches by a very weak film of rubber extending along the top corners of the ridge. The strip may be

torn along the top corners between the beads by pulling it away from the ridge 15. After the separating strip is removed the bead edges are left sufficiently smooth that no further trimming is required after the pouches are removed from the form.

The distance between the off-set positions 16 may be made of the desired length to produce a flap of any desired length, or the distance may 10 be made equal to zero and thereby produce pouches on each end without any flap.

The term "rubber" as used herein means rubber or rubber compositions containing suitable compounding ingredients either dispersed with 15 or contained in the coagulated rubber.

While the preferred forms of this invention have been shown and described herein it will be understood that the changes in the details as shown may be made without departing from the 20 spirit of the invention or the scope of the appended claim.

Having thus described my invention what I desire to claim by Letters Patent is:

An elongated deposition form having side and edge deposition surfaces for receiving a coating for the production of a pouch on each end thereof 5 having a pocket covering the outer end of the form on which it may be deposited and a flap fitting in complementary relation with the flap and mouth opening of the other pouch along the intermediate portion of said surfaces, an abruptly 10 rising ridge extending across said side deposition surfaces at off-set positions and along said edge surfaces between said off-set positions, to produce a bead on the mouth and flap of the respective pouches outlined by the opposite sides 15 of said ridge, and a handle extending through the top surface of said ridge and connected to said form.

GRAHAM G. WANLESS. 20
